UNITED STATES PATENT OFFICE.

CHARLES P. HIDDEN, OF PROVIDENCE, RHODE ISLAND, ASSIGNOR TO NITROGEN PRODUCTS COMPANY, A CORPORATION OF RHODE ISLAND.

PROCESS FOR FIXING ATMOSPHERIC NITROGEN.

1,352,193.

Specification of Letters Patent.

Patented Sept. 7, 1920.

Application filed July 5, 1919. Serial No. 308,772.

To all whom it may concern:

Be it known that I, CHARLES P. HIDDEN, a citizen of the United States, residing at Providence, in the county of Providence and State of Rhode Island, have invented 5 certain new and useful Improvements in Processes for Fixing Atmospheric Nitrogen, of which the following is a specification.

10 This invention relates to a process for fixing atmospheric nitrogen and, in its preferred form said process may be regarded as an improvement upon that described in the patent to John E. Bucher, Number 15 1,120,682, dated December 15, 1914; but whereas said known process is preferably a continuous one, that described herein is preferably of the batch type.

20 The principal aim of the present invention is to reduce the cost of fixing nitrogen in the form of a cyanogen compound, to wit, alkali metal cyanid.

25 Another object of my invention is to eliminate, in very large measure, the tendency of the charge under treatment, to adhere to the walls of its retort; especially where cooling occurs within said charge after cyanid has been formed therein, whereby the charge for a time becomes very tacky 30 and adhesive.

35 Another object of my invention is to greatly reduce the tendency for cyanid formed during the course of the Bucher process, to volatilize; such vaporized product usually being lost, as it cools, owing to its conversion to sodium carbonate or the like in the presence of the atmosphere of mixed carbon monoxid and nitrogen.

40 These and other objects of my invention will be hereinafter referred to and the novel combinations of steps which constitute my process will be more particularly pointed out in the claims appended hereto.

45 In the accompanying drawing which forms part hereof, I have exemplified a preferred furnace construction, in combination with certain auxiliary pieces of apparatus, which together with said furnace constitute a system especially well adapted to the effectuation of said process.

50 As, however, I am aware of various changes and modifications which may be made both in said process and apparatus, without departing from the spirit of my invention, I desire to be limited only by the

scope of said claims, broadly interpreted in the light of my disclosure.

Referring to the drawings:

Figure 1 is a somewhat diagrammatic, 60 vertical section of a cyanizing furnace.

Fig. 2 is a fragmentary detail section, taken on the line II—II of Fig. 1.

Fig. 3 is a similar section taken on the line III—III of Fig. 1.

Fig. 4 is the diagram showing the preferred arrangement of the different pieces of apparatus and connections therebetween.

Considering first the furnace and its more immediately associated parts: The brick-work 1 of said furnace is preferably disposed to form a chamber, the annular wall of which has been designated 2. Within this chamber is a hopper 3, the lower end of which is closed by a bell 4, carried by a rod 5, which depends from a lever 6. The latter is pivoted upon a shaft 7, which preferably extends through the walls of the gas-tight cover 8, of the hopper.

The charge to be treated, preferably in briqueted form, is introduced into the hopper 3 from an auxiliary or feed hopper 9, through a rotatable feed valve 10. This latter is of known construction and is provided with a pocket which receives a small portion of the charge and rotarily delivers 85 it to hopper 3, while at the same time cutting off communication between the latter and the outer air. The air in the interstices of the so admitted charge may be eliminated by sweeping it out with nitrogen 90 passed in through the pipe 10'. A valve of this type is shown in the United States patent to William D. Mount, No. 1,304,697, dated May 27, 1919.

The bell 4 is normally overbalanced by a 95 weight 11 upon an arm 12, secured to an end of the shaft 7.

The hopper 3 and its cover 8 may be supported by a frame 13; and the lower end of said hopper preferably abuts against a casting 14, which provides a seat for the bell 4.

Spaced a short distance below the casting 14, is the upper edge of the retort 15. In order that the charge, after treatment, may freely discharge from this retort, I prefer 105 to flare the walls of the latter outwardly and downwardly. The retort 15 is preferably supported by brackets 16, or the like, which in turn may be carried by the brick-work.

To protect the retort from the hot gases to which it is exposed, and which, if said retort be of iron, tend to soften it and thereby allow it to become deformed, I prefer to substantially surround such exposed portions by brickwork 17.

To permit retort 15 to be readily withdrawn from the furnace, its lower edge 15' is flanged or enlarged to sustain a packing 18, of kieselguhr, which surrounds the central portion of said retort. I prefer to similarly pack kieselguhr around the hopper 3, as at 19, in order to prevent ingress of air to the space below the bell 4, as well as to 15 provide heat insulation.

Below the hopper 3, and preferably spaced some inches therefrom, is a trap,—preferably made in two pieces, 20—20. When the retort 15 is loaded, the briquets 20 in its lower end flow out laterally and form a slope as at 21. To prevent such briquets from moving out too far, I provide a semicircular flange 20' around the edge of each trap section.

25 There is usually considerable space between the casting 14 and the upper surface of the charge; which surface, for purposes of illustration, I have indicated by a dotted line designated 22.

30 Each trap section may be strengthened by radial ribs 20", and said sections are separated from each other by a narrow space 23, to permit of their free and independent movement.

35 The trap sections are pivoted upon shafts 24; two shafts being provided for this purpose, one upon either side of the chamber 25 through which the charge falls when said sections are moved to their open positions.

40 Shafts 24 are journaled in brackets 26, each preferably provided with a double wall, to afford a space 26' around each shaft journal, whereby the journal may be cooled by the passage of, for example, a stream of 45 relatively cold nitrogen gas. This cooling current of nitrogen may be introduced into the journal bracket via pipe 27, to which is connected pipe 27' which leads the gas into space 26'; said gas emerging at the opposite end of the bearing through pipe 28.

50 As the system for cooling the journals may be the same in each case, I have exemplified but one set of connections for this purpose. I also prefer to make each shaft 24 hollow, 55 so that gas may be passed therethrough from pipe 27, and to provide each end of said shaft with a stuffing box 24', to afford gas-tight connections with the pipes which respectively introduce the cooling gas and

60 conduct the same away from said shaft. The semicircular traps may be keyed fast to their respective shafts, as at 29, and are of heat resistant alloy, or are otherwise similarly adapted to withstand the heat to which 65 they are subjected.

Mounted upon one end of each of the shafts 24 is a worm wheel 30, which co-acts with its worm 31 to control the disposition of the corresponding trap section. Accordingly, by rotating the shaft 32 of one of the 70 worms 31, in one direction or the other, the corresponding trap section may be swung up into its charge retaining position, or rotated down to dump the charge, either *en masse*, or more or less broken up, as is to be 75 preferred. That is to say, one section 20 may first be lowered, and then the other, or both may be lowered somewhat slowly and simultaneously, to better disrupt the charge.

I prefer to bulge up the center of the 80 trap, considered as a whole, as at 33, to aid in distributing the gases. In the construction shown by way of illustration, the line of severance between the two substantially semicircular trap sections cuts diametrically 85 across this protuberance.

The hub 34 of each trap section may conveniently be made equal in length to the radius of said section and be connected thereto by a web 34'. To afford clearance 90 for the trap sections, when the latter are being lowered, the brickwork may be cut away as at 35.

Chamber 25 is covered by a brickwork dome 36, save where the lower extremity 95 of the retort 15 closes the orifice in said dome. At spaced intervals around this dome are ports 37 in communication with a conduit 38 which extends around the retort, and which either receives gas from a conduit 39, or delivers gas to a conduit 39'.

The space above the retort 15 is in communication with a plurality of ports 40 which similarly lead into a common conduit 41, whence gas passes through a conduit 42, or enters through conduit 42'.

Chamber 25 is provided near the bottom thereof with a breaker 43, and the top of this should be sufficiently below the axes of the shafts 24, to permit the trap sections to move into their vertical positions. The preferably star-shaped breaker is massive to resist rupture when the falling charge strikes the center thereof, and its respective arms are edged, as at 43', to aid in breaking 110 up the charge.

In the walls of chamber 25 are twyers 44 through which jets of cold nitrogen may be directed into the chamber 25. The bottom of this chamber is preferably sloped inwardly and downwardly, as at 45, and the central orifice 46, therebelow is normally covered by a seal-protecting fly-gate 47, mounted upon a shaft 48. The lower edge of the orifice 46 may be provided with a flange 49', which may conveniently be formed integral with the casting 49.

A grooved pan 50, carried by a lever 51, normally seals the opening 46 substantially gas tight, through the intermediacy of 13

5 kieselguhr 52, or the like, with which the annular groove in said pan is filled. The hub of the lever 51 is mounted upon a shaft 53, at each end of which is a flanged roller 54, which rides upon a rail 55. These rails are provided with stops 55', which limit inward travel of the shaft 54, whereby to center pan 50 with respect to orifice 46. The pan 50 is overbalanced by a weight 56, which 10 may be integral with lever 51. Weight 56 normally reposes upon a plate 57.

15 I prefer to operate the so constituted valve by the following simple mechanism. Weight 56 is provided with an upturned hook 56', which is adapted to interlock with a hook 58' upon the end of a rod 58. Mounted for reciprocal motion upon plate 57, is a hollow wedge block 59, and weight 56 may be cut away as at 56'', to permit of the insertion of 20 wedge 59 therebeneath. The outer end of said wedge is provided with a boss 59', for the reception of a pipe 60 which is firmly secured to the wedge. Rod 58 is axially movable in said pipe. I prefer to provide a 25 stuffing box 61 around the pipe 60 and a corresponding box 61' upon the outer end of said pipe and around the rod 58.

Below the pan 50 is a chamber 62, the 30 lower end of which is closed by a hopper 63, within which are mounted breakers 64. These may be of any known and suitable construction and need not be herein further described, other than that I may state their 35 shafts 65, are preferably geared together, as by gears 66; one of these shafts being driven, as by a worm wheel 67. Below the breakers 64, is a staunch screw conveyer 68-68'.

40 I prefer to cool the hopper 63 externally as well as internally. To this end, air or nitrogen may be passed through the space 70 into the space 70 which surrounds said hopper, and thence out via pipe 71. Relatively cool nitrogen is introduced into said hopper through the shell 68' of the conveyer, and 45 this cools the charge in the latter, and also that portion of the charge which reposes in the hopper 63. By the time that said nitrogen has passed up through chamber 62 for emergence through the conduit 72, for storage in the receptacle 72', it is usually quite 50 hot, even before it passes into the preheater 73, shown in Fig. 4.

55 Referring now more particularly to Fig. 4, it will be noted that said preheater is adapted to heat not alone the nitrogen delivered thereto from the tank 72', but also carbon monoxid delivered to said preheater through conduit 74. A part at least of this 60 carbon monoxid may be formed in the carbon monoxid producer 75, which receives a gas, preferably consisting in large part of carbon dioxid, from the outer passage 76 of the heat interchanger; said gas passing into the producer 75 via pipe 77.

65 It may be explained at this point that the

CO₂ laden gas thus supplied to the producer, was delivered to passage 76 through a pipe 78 which received said gas from a pump 79; a pipe 80 delivering said gas to this pump from a receptacle 81, in which said carbon 70 dioxid is produced.

The receptacle 81 is preferably provided with an agitating device 82, driven by a worm and wheel 83; the shaft 84 of said device, being journaled as at 85-86, and 75 having stuffing boxes 87, to prevent ingress of air to receptacle 81.

The second passage 88, in the heat interchanger, conveys carbon monoxid from the cyanizing furnace to the receptacle 81; conduit 88 being most conveniently connected to that designated 42.

The preheater is connected to the furnace to enable the discharge of either hot nitrogen or hot carbon monoxid into the retort, as 85 desired; valves 89, 90, 91, 92, 93 and 94 being provided for this purpose. In the preferred apparatus, the connection 95 with its valve 96, affords means to introduce oxygen into the producer 75. 90

The mode of operating the apparatus and the process which may be effectuated therein will now be more particularly considered.

After the charge has been measured into hopper 3 by valve 10, the bell 4 is lowered 95 to drop said charge into retort 15; the trap sections 20 at such time being in their closed positions. An annular space is afforded at 21 through which gas may freely enter said charge at the bottom of the retort, from all 100 sides thereof.

Valves 90, 92 and 94 will be closed at this time, while valves 89, 91 and 93 will be open. The pump 79 is started, and the agitator 82 is caused to rotate slowly within 105 the receptacle 81. This receptacle contains a mass of powdered iron, nickel, or the like, which is adapted to act as a catalyst for the conversion of carbon monoxid into carbon dioxid at a suitable temperature, to wit, 110 400°-600° C. At 400° C., finely divided nickel, especially, is capable of converting carbon monoxid nearly quantitatively into carbon dioxid, with attendant deposition of pure carbon, in very finely divided form, 115 upon the catalytic mass. When the pump 79 is thus started into operation, the space in and about the retort is at first filled with a mixture of nitrogen and carbon monoxid,—the nitrogen as a result of the previous operation of the furnace,—and this mixture leaves the furnace via conduit 42 and passes thence through conduit 88 to receptacle 81. When the pump 79 is thus started into operation, the space 120 in and about the retort is at first filled with a mixture of nitrogen and carbon monoxid,—the nitrogen as a result of the previous operation of the furnace,—and this mixture leaves the furnace via conduit 42 and passes thence through conduit 88 to receptacle 81. If the furnace has just previously been in operation, this gaseous mixture will, by the time it reaches receptacle 81, be at a temperature which favors the deposition of carbon and gas containing a high percentage of carbon dioxid will then 125 pass through the pump and back by way of 130

It may be explained at this point that the

passage 76 to pipe 77. This gas will receive heat from that passing through conduit 88; so that by the time it enters the producer 75, it will be quite hot. Within the producer 5 75 is a mass of incandescent coke and as the hot CO_2 enters this producer, oxygen is also fed in through pipe 95 to react with the coke exothermically, in a known manner, the carbon dioxide, oxygen and carbon being converted into carbon monoxide; with the 10 result that hot gas having a very high content of CO , passes from the producer through pipe 74 to the preheater 73 in which its temperature is preferably raised 15 to $1,000^\circ \text{C}$., or higher. Normally the pre-heater needs to supply but little heat to this gas on account of its temperature when leaving the producer.

The gas now passes through conduit 39 20 to the distributing conduit 38, whence it flows through ports 37 into the space just below the dome 36. As the pan 50 is in its closed position at such time, said gas can not flow downwardly but is forced to enter 25 the charge, at the bottom of the retort. The stream of highly heated gas then passes through substantially all parts of the charge and flows out at the top and thence through 30 ports 40 to conduits 41 and 42. After a few preliminary cycles of the gaseous stream, the gas entering conduit 88 of the heat interchanger will be at a temperature approximating 800 to 900°C ., and its temperature will thereafter rise as the temperature 35 in the upper part of the retort 15 approaches $1,000^\circ \text{C}$., or slightly higher.

As the gas becomes more nearly pure CO , its conversion in receptacle 81 into CO_2 becomes more nearly quantitative, with the result 40 that a copious deposition of carbon is effected in this receptacle. This carbon, together with the catalyst, can be removed from time to time from receptacle 81 through the orifice 81' in the bottom of the 45 latter, and fresh catalyst can be introduced at the top; air preferably being excluded from the apparatus at all times.

The CO_2 laden current delivered to the producer through pipe 77, at such time, is 50 almost as highly heated as the gas emerging from conduit 42, if the heat interchanger be properly constructed. This reduces the consumption of oxygen and fuel in the producer 75; while it also reduces the burden 55 upon the preheater 73.

It will be understood that for economy of operation, the possibility of loss of heat by radiation from various parts of the system, is reduced to a minimum by heat insulation.

The great advantage in thus heating the whole charge by means of a stream of substantially non-cyanizing gas, rather than by externally firing the retort, is that the heating 60 operation can be conducted in very much

less time, and the charge is more uniformly heated throughout. This problem of supplying heat to the interior of the charge in question is one which has agitated the minds of those concerned with this art, for a number of years. Various methods of heating have been proposed; but it has been found in practice that hours of heating were required to cause the heat to penetrate from the walls of the retort radially to a depth 75 of even six inches into the charge. This is due to the fact that when the charge is cold, or relatively so, it is an exceedingly bad conductor of heat. As its temperature is raised, it at first very gradually changes its heat 80 conductivity, until as the reaction temperature is approached, it more rapidly becomes heat conductive.

In the process described in said patent to John E. Bucher, the gaseous current of nitrogen, of course, becomes heated during its 85 ascent through the charge, and hence, to some measure, tends to disseminate heat.

The great difficulty here was, however, that as any part of the charge approached 90 reaction temperature, the nitrogen at once reacted to form cyanid, and this notwithstanding that the entire charge was not uniformly heated. When cyanid has thus formed, it thereafter slowly volatilizes; and 95 the stronger the current of nitrogen,—especially if such current be hot,—the greater the volatilization of said cyanid.

This vaporized cyanid was then carried up by the nitrogen stream and as the top 100 of the retort was approached, the content of carbon monoxide in this gaseous current became increasingly larger. At a temperature of about 850°C ., a comparatively few 105 per cent. of carbon monoxide in the atmosphere surrounding the cyanized mass, especially if the cyanid be in vaporous condition, reconverts the cyanid to sodium carbonate. This causes a deposition of sodium carbonate in the upper relatively cool end 110 of the retort, and this increased content of carbonate aids in choking the retort, to prevent a downward movement of the charge in a continuous furnace.

The result of this volatilization of cyanid 115 which is, so to speak, prematurely formed in the retort, is that not only does it hinder the feed through the retort, but the yield of product is very materially reduced.

In the preferred form of the present process, owing to the high content of carbon monoxide in the gas supplied to the charge during the heating period, there is practically no chance for cyanid to form, while sodium carbonate does not volatilize or decompose appreciably under the conditions and at the temperature to which the charge is heated. Hence, there is no excessive production of sodium carbonate in the upper 125 end of the retort; but rather the distribu- 130

tion of said carbonate is maintained substantially uniform throughout the charge.

Assume now that the charge has been subjected to heat treatment in the furnace, until 5 its temperature is approximately 1,040° C. Valve 96 is now closed and the pump is stopped. Valves 89, 91 and 93 are also closed, and valves 90, 92 and 94 are opened. Nitrogen preheated, preferably, to about 10 1,050° C. then flows through the conduits 42'-41 and ports 40, into the space below the gas-deflecting arch 36'; whence it passes down through the charge, in substantially the same manner as the currents of carbon 15 monoxide had passed up, and thence out by ways of ports 37 and conduits 38-39'. The plate 14 and bell 4 are preferably formed of a heat resistant alloy adapted to withstand the temperature of the incoming nitrogen. 20

The current of highly heated nitrogen thus passed through substantially all parts of the already highly heated charge, causes an exceedingly rapid conversion of sodium 25 carbonate, in said charge, into sodium cyanid, in accordance with the reaction;

In this connection, considerable advantage is gained by thus causing the nitrogen current to flow oppositely to the course of the CO current through the charge; since if the CO stream enters at the bottom, the top of the charge will be less highly heated 35 than the bottom, after, say, one-half hour of heat treatment.

The hot nitrogen stream then tends to reverse this inequality, thereafter. Also, since CO is evolved during the formation of the 40 cyanid, and since the nitrogen stream is preferably pure,—there will, under the preferred conditions, be little CO present in the gas in the top of the retort, although some 8 or 10 per cent. of CO may be present 45 in the emerging nitrogen. The initially more highly heated, lower end of the charge will, however, favor cyanid formation in spite of this CO content, while the cooler upper end is constantly being more highly 50 heated by the hot nitrogen and the latter is, further, nearly pure, so that cyanid can copiously form in it, even at 850°-950° C.

Moreover, an important characteristic of the present process, especially when the hot 55 gaseous currents are reversed as aforesaid, or in any equivalent fashion, is that owing to the rapid formation of cyanid substantially simultaneously throughout the charge, there is but little loss of cyanid by volatilization.

Normally, after but comparatively few minutes of treatment with the hot nitrogen current, the latter may be shut off by closing valves 90, 92 and 94. Pipe 60 is pushed in, 60 to lock the hooks 56'-58', and rod 58 is then

pulled to completely open the pan valve 50; after which the fly-gate 47 is rotated into its vertical position. Jets of cold nitrogen may now be introduced into the chamber 25 through the twyars 44, and, at substantially 70 the same time, the shafts 32, which drive the worms 31, are rotated to cause the sections 20 to descend. The still quite highly heated charge within the retort 15, is thereby dumped or poured, so to speak, and clears 75 said retort and its trap sections before it has an opportunity to set.

This setting of the cyanized charge has caused great trouble in continuous furnaces; but the present procedure of dropping the 80 charge out of its container, while its temperature is still above that at which the mixture of cyanid and carbonate, or the like, in said charge tends to set and hence to become tacky, quite completely eliminates 85 this difficulty; and this feature is hence of great value substantially irregardless of the previous step or steps employed in effecting cyanization of the charge.

In the preferred form of the process, the 90 descending charge,—the tempearture of which had been allowed to fall to around 800°, even before the trap was opened,—is somewhat superficially chilled by the cold nitrogen blasts and impinges against the 95 breaker 43, the vanes of which smash said charge, or already broken portions thereof, into fragments.

As soon as the charge fragments have fallen into the cooling chamber 62, the pan 100 50 is moved to its closed position by pressing in upon both rod 58 and pipe 60, until the rollers 54 come to rest against the stops 55'. Pressure upon rod 58 is then maintained while the pipe 60 is 105 retracted. As the wedge 59 is withdrawn from beneath weight 56, the latter drops and frees hook 56', while at the same time the seal 52 in the groove of the pan is pushed up around the flange 49'. The fly-gate is 110 preferably closed before the pan is rolled into position to close the same, to protect the pan from any loose charge material.

The relatively cold nitrogen entering 115 through the conveyer chills the fragments of charge in the hopper 63, while at the same time the breakers 64 break these fragments into pieces adapted to be handled by the conveyer. The warm nitrogen emerging from chamber 62 may be stored in the 120 gasometer 72'.

After pan 50 has been moved to its closed position, trap sections 20 are turned up and the charge which has meanwhile accumulated in hopper 3 is allowed to descend into 125 the retort, by lowering the bell 4 as before.

During the period when nitrogen is being supplied to the charge as above described, the nitrogen in receptacle 72', augmented by the nitrogen ascending from the 130

cooling pit 62, at such time, may be passed into the preheater, via pipe 72'.

It will thus be observed that while the furnace is what may properly be termed a 5 batch furnace, its operation may be made almost continuous, and as fast as one batch has been preheated by hot CO and thereafter treated with hot nitrogen to cyanize it, it is dumped into the cooling pit, and 10 after the trap has been closed and valve 50 is moved to its closed position, the retort is ready for a new charge which meanwhile has been accumulated in hopper 3.

The cooling fragments of cyanized material are slowly removed from hopper 63 by 15 the conveyer 68—68' and may then be more completely cooled in any suitable manner, with exclusion of air, until their temperature is sufficiently low to prevent oxidation 20 of the cyanid to cyanate upon exposure of the briquets to the atmosphere.

I may here state that the charge to be cyanized in the manner described, is preferably composed of a briquetted mixture of 25 the finely divided carbon obtained from receptacle 81 (although coke or the like may also be used), finely divided iron and sodium carbonate; this mixture being prepared and briquetted substantially in accordance with the disclosure of said John E. 30 Bucher in his patent aforesaid. I do not desire to be limited to this mixture, however, as I am aware of a considerable number of mixtures which are well adapted for use in 35 connection with my process, and the term "alkalinous metal," used in certain of the claims, contemplates both the alkali and alkaline earth metals.

I also do not desire to be limited to the 40 treatment of the charge with substantially pure CO, or with nitrogen having a high CO content as a means for, in effect, idly heating the charge; as I am aware that other gases, such as argon or the like, may 45 be used for this purpose. I do regard it, however, as highly desirable that during the heat supplying stage of the process, in which the material under treatment is raised to, or substantially to, reacting temperature, 50 there shall not be present in the gas thus conveying heat to the charge, a sufficient preponderance of nitrogen to permit conversion of the carbonate, hydrate, or the like, into cyanid, to any material extent.

55 I need scarcely state that it is by no means necessary to produce carbon monoxid in the manner indicated. Neither is it essential that this gas be converted to carbon dioxid with attendant deposition of carbon 60 in the manner described. There are, however, advantages in so doing, even aside from the production of pure carbon for the process, in that, for example, the pump or the like used to circulate the gas, may be 65 operated at a relatively low temperature,

and this without waste of heat energy; while heat energy for the process is obtained in large part by the exothermic combination of oxygen and carbon in the producer 75.

As the described system produces more 70 CO than is required in the process, this more than compensates for mechanical losses and nitrogen additions. Excess of gas may be tapped off, preferably in the form of CO₂, by opening valve 78.

75 I am aware that relatively small bodies of cyanizable charge may be heated by externally firing the retort. Also that larger bodies may be heated internally, as, for example, by using the charge itself as a 80 resistor, as disclosed by said Bucher in his Patent No. 1,174,667, dated March 7, 1916; etc. In no case, however, has it been known to heat the charge to, or substantially to, reaction temperature, and then suddenly 85 change the atmosphere around said charge to vigorously promote said reaction in all parts thereof, substantially simultaneously. It is for this reason that I do not wish to be limited to heating by gaseous convection, 90 direct or otherwise, although I greatly prefer to thus heat the charge internally by direct gaseous convection.

Finally, it will be observed that while the 95 retort is preferably of iron, it is substantially unaffected by the gases conveying heat thereto, since no gas capable of oxidizing said iron is in contact therewith. This destruction of iron and of other comparatively inexpensive (and even some very expensive) 100 retorts, has proven a hitherto insuperable difficulty, where such retorts have been heated by the combustion products of producer gas, oil, or the like, on account of the high CO₂ content in the gas impinging 105 against the retort. Heating by hot CO, or its equivalent, entirely overcomes this difficulty; while, of course, it is not subject to the difficulties attendant upon electrical heating. Moreover, adequate electric current is not at all times available. I hence 110 regard the heating of the charge to be cyanized, by highly preheated carbon monoxid as the most generally advantageous solution 115 of this problem, while the conveyance of heat thereby, as is to be preferred, directly into the charge, permits of conducting the operation in a retort having a capacity practically prohibited to one which is externally fired.

120 Having thus described my invention, what I claim is:

1. In the art of fixing nitrogen by cyanizing a porous charge, constituents of which are capable of combining with free nitrogen 125 to form a cyanid and carbon monoxid,—the improvement which consists in first internally heating said charge, treated as a batch, substantially to cyanid-forming temperature, by direct gaseous convection, the gas 130

employed to carry heat into the pores of said charge being incapable of supporting the cyanid-forming reaction, then passing into said charge substantially pure nitrogen pre-heated to a temperature at which said reaction will occur, and again changing the atmosphere in the pores of said charge by passing relatively cool nitrogen therethrough, to sweep out the carbon monoxid 10 formed by said reaction while lowering the temperature of the batch being treated, below that at which carbon monoxid can deleteriously react upon the cyanid present in said batch.

15 2. In the art of fixing nitrogen by reacting with free nitrogen upon a mixture comprising an alkalinous metal compound and carbon,—the improvement which consists in first heating an intersticed mass of said mixture to a temperature at which said mixture can react with pure free nitrogen to copiously form a cyanogen compound the base of which is said alkalinous metal, by passing a heat supplying gas, which is itself incapable of causing said reaction, through the interstices in the mixture, then, while said charge is highly heated, changing the nature of the atmosphere in said interstices to rapidly form said cyanogen compound substantially throughout said mass, dumping said mass from the container in which said cyanogen compound was formed, before the liquid constituents of said mass can congeal, and thereafter cooling said mass to congeal 35 said liquid constituents.

3. In the art of fixing nitrogen by reacting in a receptacle with free nitrogen upon a porous charge constituents of which are capable of combining with said free nitrogen to form a cyanogen compound which is fluid at the temperature of said reaction and which compound renders said charge adhesive while the fluid content of said charge is solidifying at a temperature below that at 45 which said compound forms,—the improvement which consists in unloading said charge, as a batch, from said receptacle while the charge is still at a temperature above that at which it becomes adhesive, and cooling said charge in an innocuous atmosphere while breaking it into fragments.

4. In the art of fixing nitrogen by reacting in a receptacle with free nitrogen upon a porous charge constituents of which are capable of combining with said free nitrogen to form a cyanogen compound which is fluid at the temperature of said reaction and which compound renders said charge adhesive while the fluid content of said charge is solidifying at a temperature below that at 55 which said compound forms,—the improvement which consists in unloading said charge, as a batch, from said receptacle while the charge is still at a temperature above that at which it becomes adhesive.

5. In the art of fixing nitrogen by reacting in a receptacle with free nitrogen upon a porous charge comprising carbon and an alkalinous metal oxygen compound, to form a cyanogen compound of said metal,—the improvement which consists in first supplying heat to said charge while omitting to cyanize the same, by control of the atmosphere in the pores of said charge, until said charge is heated substantially to a temperature at which, if said atmosphere were pure nitrogen, said cyanogen compound would form, then changing the atmosphere in said pores, throughout the bulk of said charge, to provide an atmosphere capable of supporting the reaction yielding said cyanogen compound, whereby to copiously form said cyanogen compound, throughout said charge substantially as a whole.

6. In the art of fixing nitrogen by reacting in a receptacle with free nitrogen upon a porous charge comprising carbon and an alkalinous metal oxygen compound, to form a cyanogen compound of said metal,—the improvement which consists in first supplying heat to said charge while omitting to cyanize the same, by control of the atmosphere of the pores in the said charge, until said charge is heated substantially to a temperature at which, if said atmosphere were pure nitrogen, said cyanogen compound would form, then changing the atmosphere in said pores throughout the bulk of said charge, to provide an atmosphere capable of supporting a reaction yielding said cyanogen compound, whereby to copiously form said cyanogen compound throughout said charge substantially as a whole, unloading said charge from its receptacle and cooling it to solidify the liquid constituents thereof out of contact with said receptacle.

7. In the art of fixing nitrogen by reacting with free nitrogen upon a mixture comprising carbon and an alkalinous metal oxygen compound,—the improvement which consists in first heating an intersticed mass of said mixture to a temperature at which the said mixture can react with pure nitrogen to copiously form a cyanogen compound the base of which is said alkalinous metal, by passing through the interstices in the mixture a heat supplying gas which is itself incapable of causing said reaction, then, while said charge is highly heated, changing the nature of the atmosphere in said interstices substantially simultaneously throughout said mass, by replacing said gas by one favoring said reaction and supplying the nitrogen to be fixed thereby, whereby to coincidentally form said cyanogen compound in substantially all parts of said mass.

8. In the art of fixing nitrogen by cyanizing a porous charge constituents of which are capable of reacting with free nitrogen to form a cyanid,—the improvement which

consists in heating the said charge throughout by direct gaseous convection to a temperature at which said cyanid can copiously form, by successively passing oppositely flowing streams of heat-carrying gas through the pores of said charge.

9. In the art of fixing nitrogen by cyanizing a porous charge constituents of which are capable of reacting with free nitrogen to form a cyanid through the intermediacy of a catalyst in said charge,—the improvement which consists in heating the said charge throughout by direct gaseous convection to a temperature at which said cyanid can copiously form, but below that at which said catalyst can sinter.

10. In the art of fixing nitrogen by cyanizing a porous charge constituents of which are capable of reacting with free nitrogen to form a cyanid,—the improvement which consists in heating said charge throughout by direct gaseous convection to a temperature at which said cyanid can copiously form, by successively passing two streams of heat-carrying gas through the pores of said charge, the first of said streams being incapable of supporting the cyanid-forming reaction and the second of said streams supplying nitrogen for said reaction and promoting the same.

11. In the art of fixing nitrogen by cyanizing a porous charge constituents of which are capable of reacting with free nitrogen to form a cyanid,—the improvement which consists in heating said charge throughout by direct gaseous convection to a temperature at which said cyanid can copiously form, by successively passing two streams of heat-carrying gas through the pores of said charge, the first of said streams having a high content of carbon monoxid and being incapable of supporting the cyanid-forming reaction, and the second of said streams supplying nitrogen for said reaction and promoting the same.

12. In the art of fixing nitrogen by cyanizing a porous charge constituents of which are capable of reacting with free nitrogen to form a cyanid,—the improvement which consists in heating said charge throughout by direct gaseous convection to a temperature at which said cyanid can copiously form, by successively passing two oppositely flowing streams of heat-carrying gas through said charge, the first of said streams being incapable of supporting the cyanid-forming reaction and the second of said streams supplying nitrogen for said reaction and promoting the same.

13. In the art of fixing nitrogen by cyanizing a charge comprising carbon and an alkali metal oxygen compound, which charge is capable of reacting with free nitrogen at a temperature approximating 1,000° C., to form a cyanid of said alkali metal,—the im-

provement which consists in heating the charge initially with gas rich in carbon monoxid and at a temperature approximately that aforesaid, subsequently cooling said carbon monoxid to a temperature favoring the conversion of a considerable part of said carbon monoxid into carbon dioxid, catalytically effecting said conversion while simultaneously producing carbon for the cyanizing step of the operation, reconverting said dioxid to carbon monoxid by imparting heat to said dioxid in the presence and through the combination of carbon and oxygen, returning the so formed carbon monoxid to said porous charge at a temperature approximating 1,000° C., and cyanizing the so heated charge by replacing the hot current of carbon monoxid laden gas passing therethrough, by hot nitrogen.

14. In the art of fixing nitrogen by cyanizing a charge comprising carbon and an alkali metal oxygen compound, which charge is capable of reacting with free nitrogen, at an elevated temperature, to form a cyanid of said alkali metal,—the improvement which consists in first heating the charge internally by a current of hot gas which is incapable of promoting the cyanid-forming reaction, and then cyanizing said charge by replacing said current of hot gas by a current of hot ni- 95

15. In the art of fixing nitrogen by cyanizing a charge comprising carbon and an alkali metal oxygen compound, which charge is capable of reacting with free nitrogen, at an elevated temperature, to form a cyanid of said alkali metal,—the improvement which consists in first heating the charge internally by a circulating current of hot gas which is incapable of promoting the cyanid-forming 105 reaction, and then cyanizing said charge by replacing said current of hot gas by a current of hot nitrogen.

16. In the art of fixing nitrogen by cyanizing a charge comprising carbon and an alkali metal oxygen compound, which charge is capable of reacting with free nitrogen, at an elevated temperature, to form a cyanid of said alkali metal,—the improvement which consists in first heating the charge internally 110 by a circulating heating current of gas having normally a high carbon monoxid content, while substantially simultaneously catalytically obtaining carbon dioxid and carbon for the process during a temperature reduction 120 in said current subsequent to the emergence of said gas from the charge being heated, said current being thereafter reheated to a high temperature, preparatory to its return to said charge, in part at least by reacting 125 upon carbon with oxygen, in the presence of the carbon dioxid laden current, and cyanizing the so heated charge by substituting therewithin a current of hot nitrogen for said hot current.

17. In the art of fixing nitrogen by cyanizing a charge comprising carbon and an alkali metal oxygen compound, which charge is capable of reacting with free nitrogen, at an elevated temperature, to form a cyanid of said alkali metal,—the improvement which consists in first heating the charge internally by a circulating heating current of gas having normally a high carbon monoxid content, while substantially simultaneously catalytically obtaining carbon dioxid and carbon for the process during a temperature reduction in said current subsequent to the emergence of said gas from the charge being heated, said current being thereafter reheated to a high temperature, preparatory to its return to said charge, in part at least by reacting upon carbon with oxygen, in the presence of the carbon dioxid laden current, and cyanizing the so heated charge by substituting therewithin a current of hot nitrogen for said hot current, said nitrogen current being passed through said charge in a direction opposite to that of said heating current.
18. The process of fixing nitrogen which comprises cyanizing a charge which includes carbon and an alkalinous metal compound, in a receptacle from which said charge may be dropped, by subjecting said charge to heat and reacting thereon with free nitrogen, and then disruptively dropping said charge and subjecting the fragments thereof to a current of relatively cold nitrogen during their fall.
19. In the art of fixing nitrogen by cyanizing a charge comprising carbon and an alkalinous metal compound, which charge is capable of reacting with free nitrogen, at an elevated temperature, to form a cyanogen compound of said metal,—the improvement which consists in first heating the charge internally by a heating current of gas, thereafter reheating said current of gas preparatory to its reentry into the charge, said charge being thus heated by said gaseous current substantially to said temperature, and forming said cyanogen compound throughout said charge by substituting a current of hot nitrogen for said heating current.
20. In the art of fixing nitrogen by reacting in a receptacle with free nitrogen upon a porous charge constituents of which are capable of combining with said free nitrogen to form a cyanogen compound which is fluid at the temperature of said reaction and which compound renders said charge adhesive while the fluid content of said charge is solidifying at a temperature below that at which said compound forms,—the improvement which consists in unloading said charge, as a batch, from said receptacle while the charge is still at a temperature above that at which it becomes adhesive, and thereafter cooling said charge by flowing a current of relatively cool nitrogen in contact therewith to congeal said fluid content.

In testimony whereof I have affixed my signature, in the presence of two witnesses.

CHARLES P. HIDDEN.
